UNITED STATES PATENT OFFICE.

PAUL REINICKE, OF KÖTHEN, GERMANY.

AXLE-BEARING FOR STRAINERS.

SPECIFICATION forming part of Letters Patent No. 735,411, dated August 4, 1903.

Application filed February 4, 1903. Serial No. 141,914. (No model.)

To all whom it may concern:

Be it known that I, PAUL REINICKE, a subject of the Duke of Anhalt, residing at Köthen, in the Duchy of Anhalt, German Empire, have invented a new and Improved Axle-Bearing for Strainers, of which the following is a specification:

This invention relates to an axle-bearing for strainers in which a packing of india-rubber and metal is arranged between the axle-box and the beating-wings.

I have represented one form of construction of my improved axle-bearing in the accompanying drawing, in which is shown the bearing portion of a strainer-box, partly in side view and partly in section.

The object of my invention is to pack the axle of the beating-wings where it passes through the bearing portion of the strainer-box, and I attain that object by means of an elastic ring in connection with a metal ring located upon the axle between the nave of the beating-wings and the axle-box, the packing attained in this manner being sufficiently tight without perceptibly increasing the friction.

The oscillating axle x carries the beating-wings l , which are secured to the axle by means of the nave m . The axle is supported by the axle-box b , the flange f of which is connected with a cylindrical projection a of the strainer box or casing k by threaded bolts s and by nuts located on both sides of the flange, said projection forming the bearing portion of the strainer or its box. Between the axle-box b and the nave m the axle x is provided with the elastic ring g , consisting of india-rubber or the like, and with the metal ring i . These rings may be compressed between the parts b and m by means of the bolts s and their nuts. I prefer to shape the neighboring surfaces of the rings g and i in such a manner that the oscillatory movements of the ring g , which embraces the axle x tightly, are transmitted to the metal ring i , so as to move the same in the same manner. In the form of construction shown the ring i is funnel-shaped and the ring g forms a truncated cone, the neighboring inclinations being perfectly the same.

The outer end of the axle x carries a crank r , by means of which an oscillatory motion is

imparted to said axle, and as the nave m of the beating-wings l is fixed to the axle the pulp is forced through the slotted plate p . The rings g and i oscillate in just the same manner as the axle x , and a slight friction arises only between the metal ring i and the axle-box b . The surfaces of contact of the parts i and b are but small, and there is no difficulty in making them exactly fit one to the other. The pulp is perfectly prevented from entering between the axle x and the axle-box b , so that the movement of the axle is not in the least impeded. Pulp may enter, it is true, between the axle-box b and the bearing a ; but no damage can herefrom arise because there is no relative motion between the two parts in question.

It is obvious that care need be taken only with respect to the surfaces of contact of the parts i and b , because that is the only place where pulp could possibly enter between the axle x and axle-box b .

The nave m might be replaced by a ring or a sleeve, and the rings g and i need not consist each of one part; but they might consist of two or more parts and there might be more rings than only two, this being in every case immaterial for the subject-matter of the invention.

Having now described my invention, what I desire to secure by a patent of the United States is—

1. In a pulp-strainer, the combination of the casing a , a casing b fitting within the same but having no relative movement thereto, an axle, beating-wings thereon, and rings on the axle between the casing b and the beating-wings.

2. In a pulp-strainer, the combination of the casing a , a casing b fitting within the same and having no relative movement thereto, an axle, beating-wings thereon, a metal ring bearing against the inner face of the casing b , and a rubber ring carried by the axle, bearing against the metal ring and means for holding the rubber ring in position.

3. In a pulp-strainer, the combination of a casing a , a casing b therein, an axle, a metal ring bearing against the inner face of the casing b , and having its other end beveled inwardly, a rubber ring carried by the axle and having a cone-shaped portion engaging the beveled part of the metal ring.

4. In a pulp-strainer, the combination of a casing *a*, a casing *b* therein, an axle, a metal ring bearing against the inner face of the casing *b* and having its other end beveled inwardly, a rubber ring carried by the axle and having a cone-shaped portion engaging the beveled part of the metal ring, and means for pressing the rings together consisting of a flange on the casing *b*, bolts on the casing

engaging the flange and nuts on the bolts to adjust the pressure of the rings.

In witness whereof I have hereunto set my hand in presence of two witnesses.

PAUL REINICKE.
